US0D1040246S

(12) **United States Design Patent** (10) **Patent No.:** **US D1,040,246 S**
(45) **Date of Patent:** **** Aug. 27, 2024**

(54) **EDUCATIONAL TOY**

(71) Applicant: **ShenZhen City MaiLianShiJi Technology Co., Ltd**, Shenzhen (CN)

(72) Inventor: **Dehu Li**, Shenzhen (CN)

(73) Assignee: **ShenZhen City MaiLianShiJi Technology Co., Ltd**

(**) Term: **15 Years**

(21) Appl. No.: **29/844,230**

(22) Filed: **Jun. 28, 2022**

(30) **Foreign Application Priority Data**

Jun. 10, 2022 (CN) 202230354993.8

(51) LOC (14) Cl. 21-01

(52) U.S. Cl.

USPC **D21/475**

(57) **CLAIM**

The ornamental design for an educational toy, as shown and described.

DESCRIPTION

FIG. 1 is a perspective view of the educational toy, showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of the educational toy, in an alternate configuration; and,

FIG. 9 is a perspective view of the educational toy, in an open position.

The broken lines and the de-emphasized portions within the broken lines illustrate portions of the educational toy that form no part of the claimed design.

1 Claim, 9 Drawing Sheets
